DESIGN FOR A ROAD SIGN

Lottie Marie Summers, Dayton, Ohio

Original application October 28, 1936, Serial No. D-65,549. Divided and this application September 11, 1937, Serial No. D-71,566

Term of patent 3½ years

To all whom it may concern:

Be it known that I, Lottie Marie Summers, a citizen of the United States, residing at Dayton, in the county of Montgomery and State of Ohio, have invented a new, original, and ornamental Design for a Road Sign, of which the following is a specification, reference being had to the accompanying drawing, forming part thereof.

This application is a division of my copending

application Serial No. D-65,549 filed October 28, 1936.

The figure is a front elevational view of a road sign, showing my new design. The article is flat and of no appreciable thickness.

I claim:

The ornamental design for a road sign, substantially as shown and described.

LOTTIE MARIE SUMMERS.
